Primary Examiner—Terry A. Wallace

[57] **CLAIM**

The ornamental design for a combined spice and cruet container, as shown and described.

DESCRIPTION

FIG. 1 is a top, front, side perspective view of a combined spice and cruet container showing my new design;

FIG. 2 is a side elevational view thereof;

FIG. 3 is a top plan view thereof;

FIG. 4 is a bottom view thereof;

FIG. 5 is a sectional view taken along the line 5—5 of FIG. 2; and,

FIG. 6 is a perspective view thereof, the additional containers shown in broken lines for illustrative purposes only and forming no part of the claimed design.
